SLED CONSTRUCTION

William Flajole, Detroit, Mich.

Application September 27, 1946, Serial No. 699,941

4 Claims. (Cl. 280—12)

1

This invention relates to sleds, and more particularly to toy sleds having a single central runner, and a pair of spaced outriggers arranged on opposite sides thereof.

It is the object of this invention to provide a sled platform with a formed sled runner centrally positioned thereunder, and with the end portions of said runner being bent inwardly to support said platform, and further bent downwardly and secured at its outer ends to intermediate portions of said runner.

It is the object of this invention to provide a transverse outrigger supporting member secured forwardly to the under side of said platform, and with the outer ends being bent downwardly and having secured thereto a pair of outrigger members.

It is the further object of this invention to provide the outriggers of a hollow welded construction, consisting of a pair of formed hollow members which are adapted to be centrally welded to each other, and also to the formed ends of said outrigger supporting members which project down into said outriggers.

It is the further object of this invention to provide a runner member upon the under surface of said outriggers, with said runner member being formed as an integral part of the outriggers.

It is the further object of this invention to employ a relatively light gauge steel in the construction of the sled, with the platform reinforced by a peripheral beading as well as with a plurality of corrugations. Further, the central runner and the outrigger supporting member are reinforced by a corrugated construction.

It is the further object of this invention to construct the central runner of a pair of separately formed and aligned spaced runner members, rather than a unitary runner.

It is the further object of this invention to provide a single, central short runner which is positioned rearwardly of the sled platform, with the forward portion of said platform being supported entirely upon the two spaced outriggers.

It is the further object of this invention to provide a sled construction of the latter type, with the outrigger supporting member being pivotally mounted under the platform to permit manual steering.

It is the still further object of this invention to provide steering means for the latter construction, whereby the rear central runner is pivotally mounted, together with manual steering means forwardly mounted on the under side of said platform, and joined to said rear runner.

2

These and other objects will be seen from the following specification and claims, in conjunction with the appended drawings in which:

Fig. 1 is a plan view of the single runner sled construction.

Fig. 2 is a fragmentary side elevational section thereof on line 2—2 of Fig. 1.

Fig. 3 is an elevational section on line 3—3 of Fig. 1.

Fig. 4 is an elevational section of the sled platform taken on line 4—4 of Fig. 1.

Fig. 5 is a plan section on line 5—5 of Fig. 2.

Fig. 6 is a fragmentary plan view of a slightly different form of sled construction employing a central rearwardly positioned runner.

Fig. 7 is a fragmentary elevational section thereof on line 7—7 of Fig. 6.

Fig. 8 is a fragmentary plan view of a sled construction similar to that shown in Figures 1 and 2, but with the central runner being formed of two aligned members.

Fig. 9 is a fragmentary elevational section on line 9—9 of Fig. 8.

Fig. 10 is a fragmentary plan view of the sled construction shown in Fig. 6, with the outrigger member being pivotally supported.

Fig. 11 is a fragmentary elevational section on line 11—11 of Fig. 10.

Fig. 12 is a fragmentary plan view of the sled construction shown in Fig. 6, but with the rear central runner being pivotally mounted for steering; and

Fig. 13 is a fragmentary elevational section on line 13—13 of Fig. 12.

It will be understood that the above drawings illustrate merely several preferable embodiments of the invention, and that other embodiments are contemplated within the scope of the claims hereinafter set out.

Referring to the drawings, Figures 1 to 5, a sled construction is shown consisting of a substantially elliptically shaped platform 11 constructed of relatively thin gauge steel, as for instance, $\frac{3}{16}$ of an inch, and reinforced by a peripheral beading 12.

Said beaded construction is circularly formed as illustrated in Figures 2 and 3 and extends below the platform throughout its periphery.

Platform 11 is further reinforced by the plurality of corrugated or indented portions 13 formed in the top surface thereof. Said platform is further reinforced by the indentations 14, which form the name "SNO-ROCKET," or "SNO-ROCKETTE," embossed in the surface of said platform.

The single central runner, Figures 1, 2 and 3, is constructed of a corrugated steel of relatively thin gauge, as for instance, $\frac{1}{8}$ of an inch, and is formed with rounded outer edges 15, and central concave slotted portion 16, to greatly increase its strength.

The central runner consists of a flat portion 17, having a formed upwardly curved front portion 18, which extends rearwardly, and is formed further with an indentation 19, a flat portion 20, and an angularly and downwardly projecting portion 21, which is suitably secured as by welding at points 22, to the top surface of runner portion 17.

Portion 17 of said runner also extends rearwardly and has an upwardly curved rear portion 23, which extends inwardly with an inclined portion 24, a flat portion 25, and an angularly and downwardly extending end portion 26, which is secured as by welding at points 27 to the top surface of runner portion 17.

End members 21 and 26 of the sled runner thereby provide a reinforcement therefor to give additional strength thereto, and also to provide a more sturdy, non-yielding support for platform 11.

Referring to Fig. 1, the outer curved edges 15 of the runner portions 20 and 25, are flattened out at 27', and are secured as by welding at points 28 to the under surface of platform 11.

The front and rear beaded portions 12 of said platform are nested respectively within indentation 19 and against inclination 24, forming a part of the central runner, whereby said platform is properly positioned relative to the formed portions of its supporting central runner.

Outrigger supporting member 29 is formed of the same corrugated steel construction, with the outer curved portions 15 and central concave longitudinal slot 16. The outer curved portions 15 of outrigger support 29 are flattened out at 30', and suitably secured as by welding to the under side of platform 11. As shown in Fig. 3, member 29 has inclined portions 30, against which rest the side beaded portions 12 of platform 11.

The outer horizontal portions of member 29 terminate in the downwardly projecting portions 31, to which are secured as by welding, formed outriggers 32.

Said outriggers are hollow and consist of a pair of formed oppositely arranged members 33 and 34, which are positioned over the free ends of supporting members 31, and welded thereto, and centrally to each other along their peripheral points of contact or juncture.

Referring to Fig. 3, outrigger members 33 and 34 have the upwardly projecting formations 35, which are adapted to be welded to opposite sides of the central portion 16 of member 31. Outer member 33 has a secondary upwardly projecting portion 36 formed by bending up the central upper portion of member 33 to provide an opening therein, through which member 31 is projected.

It will be noted that each outrigger 32 carries a flat runner 37 along its lower edge, the ends 38 of which are curved upwardly to coincide and register with the upward curvature of outriggers 32.

Runners 37 may be preferably formed as an integral part of outrigger members 33 and 34, or on the other hand, may be separate with a central flange 38' projecting into members 33 and 34, and suitably welded thereto at points 39.

The bottom surfaces of outrigger runners 37 lie in a plane which is elevated relative to the bottom surface of central runner 17, whereby it is

seen that in operation said sled may be supported and balanced entirely upon the central runner, and particularly in coasting downhill. The outriggers function only during the period when the sled is not so balanced, to prevent tipping thereof.

A reinforcing bar 40, Figures 1, 2 and 3, extends below outrigger support 29, and is welded thereto at points 41, Fig. 3, to give additional rigidity to outriggers 32. Openings 42 are formed in outrigger support 29, through which a pulling rope may be secured if desired.

Referring to Figures 1 and 4, openings 43' are formed in the rear portions of platform 11, adjacent bead 12 to aid the individual in carrying the sled.

Referring to Figures 8 and 9, a slightly different form of sled construction is shown, wherein the central runner is formed in two aligned parts, i. e., the forward central runner 43 and the rear central runner 44. Said runners consist of the same corrugated steel construction described in conjunction with Figures 1 to 5.

Forward runner 43 has a bottom flat surface engaging portion 45, which curves upwardly at 46 and rearwardly with depression 47 and flat end portion 48. Runner portion 45 also extends rearwardly, curving upwardly at 49, and terminating in the flat inwardly extending end portion 50. The corrugated portions 15 of runner members 48 and 50, are flattened the same as members 27' in Fig. 1, and are suitably and centrally secured to the under side of platform 11, as by welding.

Rear central runner 44 is continuous in form and has a flat bottom portion 51, with a forward upwardly curved portion 52, which terminates in the flat rearwardly extending portion 53. Portion 51 also extends rearwardly curving upwardly at 54. Inclined portion 55 is intermediate curved portion 54 and flat portion 53. Similarly the outer curved portions 15 of portion 53 are flattened out and welded to the under side of sled platform 11.

Annular bead 12 of platform 11 at its front and rear portions, respectively registers with depression 47 in runner 43, and inclined portion 55 of aligned central runner 44.

Outriggers 32 and their support 29, are the same as described above with respect to Figures 1, 2 and 3, and their description is not repeated.

Referring to Figures 6 and 7 a slightly different form of sled is employed, wherein the front central runner 43 of Fig. 9 is omitted. Merely central rearwardly arranged runner 44 is employed; and the front end of platform 11 is supported at all times directly by outriggers 32. The construction of outriggers 32 and their support 29, are above fully described in reference to Figures 1 to 4, and their description is not repeated.

It will be understood that the sled of Figures 6 and 7 differs from the sled of Figures 1 and 9, in that a definite three-point support is provided at all times for the sled platform. Thus three runner supporting surfaces are provided.

Figures 10 and 11 illustrate a modification of the embodiment shown in Figures 6 and 7, in that steering means are provided. The construction of the sled in Fig. 10 is the same as in Figs. 6 and 7, except that outrigger support 29 is not welded to the under side of the sled platform.

On the other hand, in Fig. 10 outrigger support 29 is centrally and pivotally mounted on the under side of the sled platform. Bolt 56 centrally supported on platform 11 extends through an opening therein, and through a corresponding central opening formed in outrigger support 29.

Cotter pin 57 extends through a transverse opening in the end of bolt 56, with a suitable washer 58 being interposed between cotter pin 57 and support 29.

Leaf spring 59 is centrally mounted on bolt 60, which also is supported upon and extends through platform 11. Washer 61 on bolt 60 engages the under side of spring 59, and is locked in position by transverse cotter pin 62.

The free ends of spring 59 engage rollers or discs 63, which are supported on bolts 64, which extend down through outrigger support 29. Said rollers are retained in position by washers 65 and cotter pins 66.

By the above construction spring 59 has the tendency to straighten out outrigger support 29, and retain it in unturned position, thereby preventing wobbling thereof. On the other hand, the sled in Fig. 10 may be turned or steered by the rider's hands or feet engaging the free extending portions of outrigger supports 29.

In Figures 10 and 11 a means is illustrated for turning the outriggers to steer the sled. However, in Figures 12 and 13 means are illustrated for steering by effecting pivotal movement of rear runner 44.

Runner 44 above described is pivotally mounted centrally and rearwardly of sled platform 11, by means of the bolt 67, which is rotatably supported upon and which extends through said platform. Bolt 67 extends through spacer disc 68 and through the fitting 69 welded to runner 44.

Fitting 69 is secured to bolt 67 by key 70, so that runner 44 is adapted to rotate with bolt 67. The latter further extends down through runner 44 and is retained on its under side by washer 71 and cotter pin 72.

Lever 73 with openings 74 at its opposite ends, is centrally carried at the lower end of bolt 67 and welded thereto. Steering lever 75 is pivotally mounted and positioned forwardly on platform 11. Said lever has a bolt 76, immovably secured thereto, which extends through an opening in platform 11 and is retained in position by washer 77 and cotter pin 78. Lever 79 is centrally joined to the lower end of pivotal steering bolt 76 and welded thereto.

Corresponding openings 80 are formed at the ends of lever 79. Steering wires 81 are respectively interposed between levers 73 and 79 through their respective openings 74 and 80, as illustrated in Fig. 12.

Thus manual steering action of handle 75 effects a corresponding angular steering adjustment of rear central runner 44.

Having described my invention reference should now be had to the claims which follow for determining the scope thereof.

I claim:

1. A sled comprising a platform having a peripheral beaded outer edge, a single corrugated runner centrally secured under said platform, a transverse corrugated outrigger support secured under said platform with its ends bent downwardly, outriggers on the ends of said support consisting of hollow oppositely arranged formed outrigger halves, centrally welded to each other

and to the said end portions which extend down into said halves, and flanged runner blades on the bottom of said outriggers, with the flanged portions extending into said outrigger halves and welded thereto.

2. A sled comprising a platform having a peripheral beaded outer edge, and a single corrugated runner centrally secured thereto, and consisting of a flat bottom portion terminating in upwardly and inwardly curved portions, adjacent flat portions secured under said platform, and angularly arranged reinforcing end portions which extend down and are secured to said bottom portion.

3. A sled comprising a platform having a peripheral beaded outer edge, a single corrugated runner centrally secured thereto and consisting of a flat bottom portion terminating in upwardly and inwardly curved portions, adjacent flat portions secured under said platform, and angularly arranged reinforcing end portions which extend down and are secured to said bottom portion, a transverse outrigger support secured under said platform, and outriggers secured upon the outer ends of said support.

4. A sled comprising a platform having a peripheral beaded outer edge, a single corrugated runner centrally secured thereto and consisting of a flat bottom portion terminating in upwardly and inwardly curved portions, adjacent flat portions secured under said platform, and angularly arranged reinforcing end portions which extend down and are secured to said bottom portion, a transverse outrigger support secured under said platform, and outriggers on the ends of said support consisting of hollow formed outrigger halves, centrally secured to each other and to the end portions of said support.

WILLIAM FLAJOLE.
